(57) CLAIM

The ornamental design for an access control keypad, as shown and described.

DESCRIPTION

FIG. 1 is a front right-side perspective view of an access control keypad, the characteristic feature of which resides in the transparent and/or translucent numbers and symbols on the keypad;

FIG. 2 is a top plan view of the access control keypad; FIG. 3 is a bottom plan view of a box to which the keypad is mounted;

FIG. 4 is a right-side elevation view of the access control keypad;

FIG. 5 is a left-side elevation view of the access control keypad;

FIG. 6 is a top-side elevation view of the access control keypad; and,

FIG. 7 is a bottom-side elevation view of the access control keypad.

The broken lines are shown for environmental purposes only and show a box to which the keypad is mounted which does not form part of the claimed design.
